UNITED STATES PATENT OFFICE.

HAROLD A. HAWN, OF GRAND RAPIDS, MICHIGAN.

REFRIGERATOR.

Application filed January 19, 1926. Serial No. 82,243.

This invention relates to improvements in refrigerators especially adapted for dispensing ice cream or for similar purposes.

The objects of the invention are:

5 First, to provide an improved construction and arrangement of refrigerating means particularly adapted to an ice cream cabinet:

10 Second, to provide an improved supporting means for the ice container and ice cream cans within such cabinet to insure a high degree of refrigeration by facilitating circulation of the refrigerated air.

15 Third, to provide a refrigerator cabinet with an improved support and arrangement and cover means whereby a series of cans are made available with very little manipulation.

20 Further objects relating to details of construction and operation will appear from the detailed description to follow. The invention is defined in the claims.

25 A structure which is a preferred embodiment of my invention is illustrated in the accompanying drawing, forming part of this application, in which:

30 Fig. 1 is a detail perspective view of my improved ice cream cabinet refrigerator, of three cans capacity, two of the covers being shown in position, one with the lid removed.

35 Fig. 2 is an enlarged detail vertical sectional view on line 2—2 of Figs. 1 and 3, showing the structure and arrangement and disposition of the refrigerant container and of the ice cream can and their spacing and support to provide for circulation.

40 Fig. 3 is an enlarged detail longitudinal sectional elevation view on line 3—3 of Figs. 1 and 2, showing the supporting rack arrangement and the spacing means for insuring circulation and the interlapping shouldered means on the interchangeable cover sections.

45 Fig. 4 is a detail perspective view of one of the refrigerant containers with its strainer cover partially broken away.

50 Fig. 5 is a detail longitudinal sectional view showing an adaptation of a cover to use as a support for a soda fountain syrup container.

55 Fig. 6 is a detail perspective view of a refrigerant container adapted to mechanical refrigeration, a portion of the wall being broken away, showing a mechanical

means for refrigeration of brine contained therein.

The parts will be referred to by numerals of reference which identify like parts in all the views.

60 1 is the outer casing of an ice cream refrigerator cabinet embodying the features of my invention. 2, 2 are the usual base supports for the same. 3, 3 are the side walls and 4 is the bottom. 5 is the inner metallic lining having an inclined bottom, vertical back and slightly inclined front. The lining is flanged at 51 and retained in place by the top frame structure. Insulation 6, preferably of cork, is provided 65 between the lining and the outer casing. The outer casing is preferably made impervious to moisture by sheet metal 3' or other means. The top structure is completed by longitudinal rails 7, 7 on which 70 are superposed the end cross rails 8, 8, the one at the right having a slight inward projection and the one at the left being jogged outwardly somewhat to form ledges 75 for engagement with the cover sections. 80

85 The cover is made up of three interchangeable sections 9, the left sides of which are provided with overhanging projections 94 and the right sides with inclined projections 95 that interengage with each other and with the end cross rails. The ends of the cover sections rest on the side rails. Lid openings 91 are provided in these covers opposite the ice cream cans within and are covered by lids 92, all of which are provided 90 with insulation 93 and are suitably metal lined.

95 As indicated in Fig. 5, a syrup container can be let into the cover back of the lid where it will be in convenient position for dispensing syrup with the ice cream.

100 Within the cabinet vertical spacers 10 are provided at the back wall, extending down across the inclined floor at 11 and up at the front at 12, forming an open space for the circulation of refrigerated air. On the bottom strip 11 are supports 13 for the ice can or refrigerant container 14. The front of the ice can is inclined forwardly to overhang the ice cream can 15, which rests upon the bottom strips 11 in spaced relation from the bottom and in inclined position against the front wall. The ice cream can does not extend entirely to the top of the casing and of course may be provided with a cover, 110

which is usually removed during business hours.

The refrigerant container 14 is provided with a handle 141 and with a strainer lid 142 which is hinged at 143. This container can of course be readily removed by the handle and the brine drained out for repacking.

In use the can 14 is ordinarily filled with crushed ice and then about one-fourth its weight of salt is placed on top. This is of course a very active freezing mixture and causes strong refrigeration of the surrounding air. The cold air drops down at the back of the can and at the front drops down into contact with the back side of the can 15 and immediately circulates under the said can 15 and rises between the front slats 12 above the top of the can and circulates back through the open space above the can, and is thus very effective in completely refrigerating the can and its contents. The cold air not only surrounds the can 15 but flows over its top into the interior when the can cover is removed, and flows across the same and is continuously refrigerated and circulated so long as the refrigerant is active. The spacing of the refrigerating element is of the highest consequence and because of the use of salt upon the ice is very active and strong, producing a temperature far below freezing. Where mechanical refrigeration is used, the tank 16 may become a brine tank and be cooled by the usual mechanical refrigerant means 161, shown in Fig. 6.

Having thus described my invention, what I claim as new and desire to secure by Letters Patent is:

1. A cabinet refrigerator comprising an outer open top insulated casing, an interior lining with bottom inclined toward the front

and with inclined front wall, spacer strips on said walls and bottom, and supports with level tops resting on said bottom spacers at the rear, a cylindrical can supported on said bottom spacer strips and resting against the inclined front spacer strips, a refrigerant container with inclined front portion and level bottom adapted to rest on said supports in spaced relation to the rear wall against the rear spacer strips and to the rear of and overhanging the rear portion of said can, and removable covers for the top of said casing, coacting as specified. 45

2. A cabinet refrigerator comprising an outer open top insulated casing, an interior lining with inclined front wall, spacer strips on the walls and on the bottom, a can supported on the bottom spacer strips and resting against the inclined front spacer strips, a refrigerant container with inclined front portion in spaced relation to the rear wall against the rear spacer strips and to the rear of and overhanging the rear portion of said can, and removable covers for the top of said casing, coacting as specified. 50

3. A cabinet refrigerator comprising an outer open top insulated casing, an interior lining with inclined front wall, spacer strips on the walls and on the bottom, a can supported on the bottom spacer strips and resting against the inclined front spacer strips, a refrigerant container in spaced relation to the rear wall against the rear spacer strips and to the rear of said can, and removable covers for the top of said casing, coacting as specified. 60

In witness whereof I have hereunto set my hand.

HAROLD A. HAWN.
